US0D1029245S

(12) **United States Design Patent** (10) Patent No.: **US D1,029,245 S**
(45) Date of Patent: ** May 28, 2024

(54) **SYRINGE CONNECTOR**

(71) Applicant: **TOLMAR INTERNATIONAL LIMITED**, Dublin (IE)

(72) Inventors: **James Sherman**, Timnath, CO (US);
Casey Dean, Fort Collins, CO (US);
Carl Hart, Lakewood, CO (US); **John Bingham**, Elizabeth, CO (US)

(73) Assignee: **TOLMAR INTERNATIONAL LIMITED**, Dublin (IE)

(**) Term: **15 Years**

(21) Appl. No.: **29/843,616**

(22) Filed: **Jun. 22, 2022**

(51) LOC (14) Cl. **24-02**

(52) U.S. Cl.

USPC **D24/129**

(57) **CLAIM**

The ornamental design for a syringe connector, as shown and described.

DESCRIPTION

FIG. 1 is a front perspective view of the syringe connector; FIG. 2 is a rear perspective view thereof; FIG. 3 is a front elevation view thereof; FIG. 4 is a rear elevation view thereof; FIG. 5 is a right elevation view thereof; FIG. 6 is a left elevation view thereof; FIG. 7 is a top plan view thereof; and, FIG. 8 is a bottom plan view thereof.

The dashed lines showing portions of a syringe connector are provided for the purpose of illustrating unclaimed subject matter and form no part of the claimed design.

1 Claim, 8 Drawing Sheets
